**HYDROREFINING HEAVY OILS USING A
PSEUDO-DRY CATALYST**

William K. T. Gleim, Island Lake, Ill., assignor to
Universal Oil Products Company, Des Plaines, Ill.,
a corporation of Delaware

Filed July 2, 1962, Ser. No. 206,919
10 Claims. (Cl. 208—264)

This invention relates to a process for upgrading heavy hydrocarbon stocks in the presence of hydrogen and a catalyst. More particularly, the present invention is directed to an improved catalytic hydrorefining process for effecting in a single operation the substantial removal of various types of impurities, as hereinafter described, from crude oil, crude residua, and heavy distillates obtained therefrom.

Crude petroleum oil, topped crude, and other heavy hydrocarbon fractions and/or distillates derived therefrom contain various nonmetallic and metallic impurities. Among the nonmetallic impurities are nitrogen, sulfur and oxygen which exist in heteroatomic compounds and are often present in relatively large quantities. Nitrogen is undesirable because it rapidly poisons various catalysts which may be employed in the conversion of petroleum fractions; in particular, nitrogen must be removed from all catalytic hydrocracking charge stocks. Nitrogen and sulfur are also objectionable because combustion of hydrocarbonaceous fuels containing these impurities releases nitrogen oxides and sulfur oxides which are noxious, corrosive and present a serious problem in the field of air pollution. Sulfur, of course, is deleterious in motor fuels because of odor, gum formation and decreased lead susceptibility.

Another class of undesirable constituents found in crude oil and residual oils are asphaltenes which are non-distillable, oil-insoluble, high molecular weight coke precursors containing sulfur, nitrogen, oxygen and metals; they are colloidally dispersed in raw crude oil but when subjected to heat, as in vacuum distillation, the asphaltenes flocculate and polymerize thereby making their conversion to more valuable oil-soluble products extremely difficult; thus, in the heavy bottoms from a reduced crude vacuum distillation column, the polymerized asphaltenes are solid materials at ambient temperature. Such product is useful only as road asphalt or, when cut back with middle distillates, as low grade fuel and commands a price substantially below that of the raw crude oil itself.

The most common metallic contaminants are nickel and vanadium, although other metals including iron, copper and zinc are often present. These metals may occur as suspended metal oxides or sulfides or water-soluble salts which may be removed, at least in part, by filtration, water-washing, electric desalting, or other fairly simple physical means; mainly, however, the metals occur as thermally stable metallo-organic complexes such as metal porphyrins and derivatives thereof. Most of the metallo-organic complexes are linked with the asphaltenes and become concentrated in residual fractions, but some of the remaining metallo-organic complexes are volatile, oil-soluble, and are therefore carried over in distillate fractions. Reducing the concentration of the metallo-organic complexes is not easily achieved, at least to the extent that the crude oil or other heavy hydrocarbon charge stock may be made suitable for further processing. Even though the concentration of these metallo-organic complexes may be relatively small in distillate oils, for example, often less than about 10 p.p.m. as the elemental metal, subsequent processing techniques are often adversely affected thereby. For example, when a hydrocarbon charge stock containing metallo-organic compounds, such as metal porphyrins, in excess of about

2

3.0 p.p.m. calculated as the elemental metal, is subjected to hydrocracking or catalytic cracking for the purpose of producing lower-boiling components, the metals deposit upon the catalyst, the concentration thereof increasing with time. Since vanadium and the iron group metals favor dehydrogenation activity, at cracking temperatures, the resulting contaminated hydrocracking or cracking catalyst produces increasingly excessive amounts of coke, hydrogen and light hydrocarbon gases at the expense of more valuable liquid product until eventually the catalyst must be subjected to elaborate regeneration techniques or be replaced with fresh catalyst. The presence of excessive quantities of metallo-organic complexes adversely affects other processes including catalytic reforming, isomerization, hydrodealkylation, etc. Vanadium itself is also objectionable in heavy fuel oils and residual solids used as fuels because vanadium pentoxide formed during combustion is a strong acid at high temperature and will corrode the refractory lining, tube supports and other internal hardware of a fired heater utilizing such fuel.

The desirability of removing these impurities is obvious and well known to workers in the art. Heretofore in the field of catalytic hydrotreating, two principal approaches have been advanced: liquid phase hydrogenation and vapor phase hydrocracking. In the former type of process, the oil is passed upwardly in liquid phase and in admixture with hydrogen through a fixed bed or slurry of subdivided catalyst; although perhaps effective in removing oil-soluble metallo-organic complexes, it is relatively ineffective against oil-insoluble asphaltenes which are colloidally dispersed in the charge with the consequence that the probability of effecting simultaneous contact between catalyst particle, asphaltene molecule and hydrogen is remote, at least at space velocities which are commercially attractive. Furthermore, since the hydrogenation zone is at elevated temperature, the retention of unconverted asphaltenes suspended in a free liquid phase oil for too long a time will result in their flocculation which makes their conversion even more difficult. Also, the efficiency of hydrogen-to-oil contact obtainable by bubbling hydrogen through an extensive liquid body is relatively low. Vapor phase hydrocracking is carried out with either a fixed bed or expanded bed system at temperatures at substantially above 950° F.; while it obviates to some extent the drawbacks of liquid phase hydrogenation, it is not well suited to treating crude oil and residual oil because of high coke make and resultant rapid deactivation of the catalyst which requires high capacity catalyst regeneration equipment in order to implement the process on a continuous basis; furthermore, selective cracking of a wide boiling range charge stock is not easily obtained, and excessive amounts of light gases are produced at the expense of more valuable intermediates; also, when charging crude oil, a minimum limit on cracked gasoline production is unavoidable which is not always desirable where the refiner wishes to maximize production of middle and heavy distillates such as jet fuel, diesel oils, furnace oils and gas oils.

A principal object of the present invention is to hydrorefine a heavy oil under conditions which simulate a vapor phase operation but which involve only minimal cracking which is selective toward asphaltenes, whereby to effect a very substantial reduction in the asphaltene content of the charge stock through conversion thereof to oil-soluble hydrocarbons.

Another object of the present invention is to substantially eliminate metallic contaminants present in a heavy hydrocarbon charge stock.

Another object of this invention is to lower materially the concentration of non-metallic impurities, e.g., nitrogen, sulfur and oxygen, present in a heavy oil whereby to

eliminate or reduce the cost of whatever subsequent distillate treating facilities may be required.

A further object of this invention is to provide a process for upgrading heavy oils under extremely mild hydro-cracking conditions which maximize middle and heavy distillate production.

The process of the present invention can be characterized as a mixed phase combination hydrorefining-stripping operation employing a fluid bed of pseudo-dry hydrogenation catalyst. It has been found that a hydrogenation catalyst comprising a porous, refractory inorganic oxide carrier having a well developed pore structure has the ability to sorb into its pore structure a substantial quantity, e.g., up to about 50% by weight, of high-boiling hydrocarbons while yet appearing ostensibly dry and free-flowing. Such non-agglomerated oil-bearing catalyst is designated herein as a "pseudo-dry" catalyst; representative compositions and physical characteristics of suitable catalytic composites are set forth more fully hereinbelow. It has further been found that converted asphaltenes, that is, asphaltenes which have been hydrorefined under mild hydrogenative cracking conditions to yield oil-soluble high-boiling hydrocarbons, comprise an excellent solvent for untreated asphaltenes which are themselves pentane-insoluble and are colloidally dispersed in a crude oil charge or agglomeratively dispersed in a topped crude oil charge. The untreated asphaltenes are much more readily converted to oil-soluble product when initially dissolved in such solvent than when directly treated in a dispersed phase suspended in liquid carrier. The asphaltene solvent is sorbed into the pseudo-dry hydrogenation catalyst particles and is preferentially retained thereby, as against lower boiling portions of the hydrotreated charge stock, when said particles are subjected to contact with a gaseous stripping medium. The instant invention utilizes the foregoing properties to effect in a singly hydrotreating zone the substantial removal of asphaltenes, metals, nitrogen, oxygen and/or sulfur from heavy oils containing same.

A broad embodiment of the present invention relates to a process for hydrorefining a heavy hydrocarbon oil which comprises maintaining in a hydrorefining zone under hydrorefining conditions a pseudo-dry fluidized bed of absorptive hydrogenation catalyst particles, partially vaporizing said heavy oil by preheating it in the absence of catalyst to a temperature below that at which any substantial thermal cracking thereof can occur, introducing the partially vaporized oil into said hydrorefining zone and contacting it in the presence of hydrogen with said catalyst particles, sorbing unvaporized oil into said catalyst particles to avoid any substantial accumulation of free liquid phase oil within the hydrorefining zone, flowing a hydrogen-containing gas upwardly through said hydrorefining zone and therewith stripping hydrorefined oil from the catalyst particles, withdrawing from said hydrorefining zone vaporous effluent and recovering therefrom a hydrorefined product of improved purity.

Another embodiment of the present invention is directed to a process for hydrorefining a heavy hydrocarbon oil containing asphaltenes which comprises partially vaporizing the oil by preheating it to a temperature below that at which any substantial thermal cracking thereof can occur; maintaining in a hydrorefining zone under hydrorefining conditions a pseudo-dry fluidized bed of absorptive hydrogenation catalyst particles having sorbed therein a liquid-phase asphaltene solvent comprising hydrorefined asphaltenes; introducing said partially vaporized oil into said hydrorefining zone and contacting it in the presence of hydrogen with said solvent-bearing catalyst particles; sorbing unvaporized oil into said solvent-bearing catalyst particles whereby to avoid any substantial accumulation of free liquid phase oil within the hydrorefining zone, and dissolving in the particle-held solvent the asphaltenes contained in the sorbed oil; converting said dissolved asphaltenes into additional asphaltene sol-

vent; flowing a hydrogen-containing gas upwardly through said hydrorefining zone and therewith stripping hydrorefined oil from the catalyst particles but leaving sorbed therein a portion of said asphaltene solvent; contacting the resulting stripped solvent-bearing catalyst particles with additional incoming heavy oil; and withdrawing from said hydrorefining zone vaporous effluent and recovering therefrom hydrorefined oil of reduced asphaltene content.

A more limited embodiment of this invention provides a process for hydrorefining a heavy hydrocarbon oil which comprises maintaining in a hydrorefining zone, at a temperature in the range of about 650-950° F. and a pressure in the range of about 500-5000 p.s.i.g., a pseudo-dry fluidized bed of absorptive hydrogenation catalyst particles; partially vaporizing said heavy oil by preheating it in the absence of catalyst to a temperature in the range of about 500-900° F. but below that temperature at which any substantial thermal cracking thereof can occur; charging the partially vaporized oil into said hydrorefining zone at a rate of about 0.25-20 pounds of total oil charged per pound of catalyst present in said zone per hour and therein contacting said partially vaporized oil in the presence of hydrogen with said catalyst particles; sorbing unvaporized oil into said catalyst particles to avoid any substantial accumulation of free liquid phase oil within the hydrorefining zone; flowing a heated hydrogen-containing gas upwardly through said hydrorefining zone at a rate of about 5,000-300,000 standard cubic feet per barrel of oil charged and therewith stripping hydrorefined oil from the catalyst particles; and withdrawing from said hydrorefining zone vaporous effluent and recovering therefrom a hydrorefined product of improved purity.

Many types of heavy hydrocarbon oils may be treated by means of this invention including full boiling range crude oil, topped or reduced crude oil, atmospheric distillates, heavy cycle oils from thermally or catalytically cracked stock, light and heavy vacuum gas oils, etc. The instant process is particularly well adapted to hydrorefining stocks containing oil-insoluble asphaltenes such as crude oil and crude residua; of these, crude oil is a preferred stock because the oil-insoluble asphaltenes being in their native environment are colloidally dispersed and thus more readily converted to oil-soluble hydrocarbons, whereas the asphaltenes in reduced crude have already been agglomerated to some extent by reason of the reboil temperature of fractionation and are therefore less easily converted. Another obvious advantage in hydrotreating crude oil in toto, rather than fractions thereof, is that subsequent separate treating steps of individual cuts may be eliminated to a considerable extent. The instant process is, however, also well suited to upgrading distillate stocks containing oil-soluble resins and maltenes and/or other of the above-discussed metallic and non-metallic contaminants, and may be employed, for example, as the feed preparation unit to a catalytic hydrocracking process for the conversion of cycle oils and gas oils.

As above noted this invention broadly involves contacting a mixed phase heavy oil charge with hydrogen and a pseudo-dry particle-form hydrogenation catalyst maintained in a fluidized state under conditions which suppress cracking in excess of the extent necessary to convert or remove impurities and which avoid accumulation of a body of liquid phase oil within the hydrorefining zone. Conditions of temperature and pressure within the hydrorefining zone are not particularly critical, provided only that they are consonant with the foregoing principles, and the exact specification thereof will depend primarily upon the nature of the charge stock. Pressure should be in excess of about 500 p.s.i.g. with an upper economic limit of about 5000 p.s.i.g., the preferred pressure range being about 1000-3000 p.s.i.g. Hydrorefining temperatures will range from about 650° F. to about 950° F. Higher temperatures are permissible and desirable for lighter charge stocks such as cycle oil and gas

oil than for heavier charge stocks. When charging total crude oil, for example, the preferred hydrorefining temperature range is about 650-850° F., and in no event should the temperature here exceed about 900° F. above which excessive cracking and coke laydown on the catalyst and apparatus internals occur. Under the desired minimal cracking conditions, hydrogenation predominates over cracking to the extent that the process is slightly exothermic.

In carrying out this process it is important to minimize cracking, both thermal and catalytic, of the heavy oil charge prior to its introduction into the hydrorefining zone, while yet imparting sufficient heat thereto to vaporize its lower boiling components and bring the total charge reasonably close to hydrorefining temperature. This is accomplished by preheating the heavy oil charge, in the absence of catalyst and preferably in admixture with hydrogen, to a temperature sufficient to partly vaporize it but below the temperature at which substantial thermal cracking thereof can occur. Generally speaking, the charge should be preheated to a temperature within the range of about 500-900° F. and preferably in the range of about 650-800° F. Thermal cracking within the hydrorefining zone proper is substantially avoided by immersing the point or points of mixed phase oil introduction in a hydrogen atmosphere so that the hot incoming oil is assured of initially contacting the catalyst in the presence of hydrogen; such hydrogen atmosphere is preferably provided by introducing a hydrogen-containing gas into the hydrorefining zone below the feed introduction point and flowing both hydrogen and feed concurrently upwardly through the fluidized catalyst bed.

Maintaining a pseudo-dry fluidized catalyst bed and preventing formation of free liquid phase oil within the hydrorefining zone are essential elements of the present process whereby to furnish a high concentration of active catalyst sites in relation to asphaltene and metal porphyrin molecules, to avoid flocculation of asphaltenes, and to minimize cracking and coke formation which contribute to rapid catalyst deactivation and loss of liquid product. Such a system is realized by the conjunctive effect of the following factors: (1) partial vaporization of the feed stock as above described, (2) use of absorptive hydrogenation catalyst particles, (3) employing a relatively low oil:catalyst weight ratio, and (4) employing a relatively high hydrogen:oil ratio. A stream of hydrogen-containing gas, which in a commercial process may contain up to 50% of vapors other than hydrogen is passed upwardly through the catalyst bed at a rate within the range of from about 5,000 to about 300,000 standard cubic feet of hydrogen per barrel of total oil charged, and preferably in the range of about 10,000-200,000 standard cubic feet per barrel. This hydrogen-containing stream, herein designated as "recycle hydrogen" since it is conveniently recycled externally of the hydrorefining zone, fulfills a number of functions; it serves as a hydrogenating agent, a fluidizing medium, a heat carrier and a hydrocarbon stripping medium. In particular, the high recycle hydrogen rate decreases the partial pressure of the oil vapor and increases vaporization of the oil without raising it to thermal cracking temperature, and maintains the catalyst bed substantially isothermal so that no vertical temperature gradient exists. The weight hourly space velocity of the charge, specified here as the weight ratio of total oil charged to catalyst contained in the hydrorefining zone per hour is within the range of about 0.25-20 pounds of oil per pound of catalyst per hour, and preferably in the range of about 1-5 pounds of oil per pound of catalyst per hour. When the heated mixed phase hydrocarbon charge is initially contacted with absorptive hydrogenation catalyst particles, the heavier liquid phase portion of the charge is partly sorbed into the catalyst particles and partly entrained in the upflowing hydrogen stream as fine droplets; the already vaporized portion of the charge is swept upwardly through the catalyst bed by the hydrogen

5

stream while the lighter liquid phase portion of the charge is vaporized by contact with hot catalyst particles and hydrogen. By virtue of the combined effects of vaporization, gas stripping and sorption by catalyst, no free liquid phase oil can form within the hydrorefining zone. The non-volatilized oil is sorbed into the catalyst particles which, however, remain dry and free flowing. This heavy fraction, which is rich in impurities, is thus exposed to a large number of active catalyst sites and is subjected to mild cracking and hydrogenation under the most favorable conditions to yield lower-boiling hydrocarbons of substantially reduced impurity content. The upflowing hydrogen stream strips off from the catalyst particles the lower-boiling hydrorefined oil as it is formed. The effluent from the hydrorefining zone is passed through an upper particle separation zone and is withdrawn from the upper portion thereof as a substantially catalyst-free, vaporous stream comprising hydrogen, light hydrocarbon gases, oil vapors, and which may contain some entrained liquid droplets. Hydrorefined oil is recovered from this overhead stream, while the hydrogen separated therefrom is returned to the hydrorefining zone together with outside hydrogen to replenish the net hydrogen consumption which may range from 200-2000 standard cubic feet per barrel of charge depending upon the nature of the charge.

The pseudo-dry catalyst system is especially advantageous where the heavy oil charge contains oil-insoluble asphaltenes, which are very effectively converted by the autosolvent hydrorefining mechanism inhering in this process. As previously pointed out, asphaltenes which have been hydrorefined under mild hydrogenative cracking conditions to yield oil-soluble high-boiling hydrocarbons comprise an excellent solvent for untreated asphaltenes which are themselves pentane-insoluble and are colloidally dispersed in a crude oil charge. Through proper correlation of weight hourly space velocity and recycle hydrogen rate, not all of the hydrorefined oil is removed from the catalyst particles by hydrogen stripping, but a portion of the hydrorefined asphaltenes, which are among the highest boiling components of the hydrorefining zone effluent, is left sorbed in the catalyst particles to act as a solvent for incoming asphaltenes and reaches an equilibrium level in a lined-out operation. The heavier liquid phase portion of the raw charge, rich in asphaltenes, is sorbed into the catalyst particles and the asphaltenes are then dissolved in the particle-held solvent thereby accelerating their conversion via selective hydrocracking to additional asphaltene solvent. Part of the solvent is stripped from the particles by the hydrogen stream, but the remainder of the solvent is left sorbed therein to dissolve additional incoming asphaltenes. The untreated asphaltenes contained in the heavy oil charge therefore constitute a continuous source of asphaltene solvent by autogeneration in situ and preferential retention thereof by the absorptive hydrogenation catalyst particles.

Non-metallic impurities such as nitrogen, sulfur and oxygen are converted by the present process to ammonia, hydrogen sulfide and water respectively, which are removed from the hydrorefining zone together with the mixed-phase effluent stream. Metallic impurities such as nickel, iron and vanadium are deposited upon the catalyst and gradually build up in concentration; although catalyst activity is not particularly impaired thereby under the condition utilized herein, it may be desirable to withdraw, continuously or intermittently, a small slipstream of catalyst from the hydrorefining zone, to chemically regenerate it by any suitable means such as treating with hydrogen chloride and/or chlorine to volatilize the metals, and to return the regenerated catalyst of reduced metal content to the hydrorefining zone.

The hydrogenation catalyst of the present invention can be broadly characterized as comprising a metallic component having hydrogenation activity composited with a refractory inorganic oxide carrier of synthetic or natural

origin having a medium-to-high surface area and a well-developed pore structure as is familiar to those skilled in the art of hydrocarbon catalysis. The composition and method of manufacturing the catalyst is not important to the present invention save only that it have the necessary absorbency to retain substantial amounts of liquid phase material within its pores in order to operate as a pseudo-dry system. Suitable metallic components having hydrogenation activity are the metals of Groups VB, VIB, and VIII of the Periodic Table, e.g., vanadium, niobium, tantalum, molybdenum, tungsten, chromium, iron, cobalt, nickel, platinum, palladium, iridium, osmium, rhodium, ruthenium, and compounds thereof. The hydrogenation catalyst may comprise any one or combination of any number of such metals which may exist in the elemental state or as the oxides or sulfides thereof in varying degrees of oxidation. The catalytic concentration of the metallic component or components, stated here on the basis of the elemental metal, will depend primarily on the particular metal involved; for example, the Group VI metals are preferably present in an amount within the range of about 1-20% by weight, the iron group metals in an amount within the range of about 0.2-10%, and the platinum group metals in an amount within the range of about 0.01-5%. Suitable refractory inorganic oxide carriers include alumina, silica, zirconia, magnesia, titania, thoria, boria, strontia, hafnia and mixtures of two or more oxides such as silica-alumina, silica-zirconia, silica-magnesia, silica-titania, alumina-zirconia, alumina-magnesia, alumina-titania, magnesia-zirconia, titania-zirconia, magnesia-titania, silica-alumina-zirconia, silica-alumina-magnesia, silica-alumina-titania, silica-magnesia-zirconia, silica-magnesia-titania, etc. The carrier may comprise additional promoters such as combined halogens, particularly fluorine or chlorine, boric acid, phosphoric acid and boron phosphate. The carrier may be formed by any of numerous techniques known to those skilled in the art such as acid-treating a natural clay, coprecipitation or successive precipitation from hydrosols, frequently coupled with one or more activating steps including hot oil aging, steaming, drying, oxidizing, reducing, calcining, etc. The pore structure of the carrier, commonly defined in terms of surface area, pore diameter and pore volume, may be developed to within specified limits, for example, by aging the hydrosol and/or hydrogel under controlled acidic and/or basic conditions at ambient or elevated temperature, by gelling the carrier at a critical pH, or by treating the carrier with various inorganic or organic reagents. The catalytically active metallic component or components may be composited with the carrier by impregnating the freshly precipitated or finished carrier with a solution of a soluble metal compound or by coprecipitating the metal with the carrier from an aqueous solution thereof. A hydrogenation catalyst appropriate for use in the present invention will have a surface area of about 50-700 square meters per gram, a pore diameter of about 20-300 Å, a pore volume of about 0.10-0.80 milliliter per gram, and an apparent bulk density of about 0.20-0.80 gram per cubic centimeter. Measurement of surface area, pore diameter and pore volume of catalytic composites may be done according to the methods set forth in *Catalysis*, volume I, pp. 37-40, Reinhold Publishing Company (1954). The catalyst particles themselves preferably should have diameters ranging from about 5 to about 1000 microns in order to function properly in a fluidized bed; in the case of non-spherical particles the maximum dimension of such particle should fall within this range. Particle sizes of this magnitude may be readily achieved by spray-drying the carrier or by grinding the catalyst in a colloid mill. By way of specific example, a very satisfactory hydrogenation catalyst comprises 2% nickel and 16% molybdenum on an equimolar alumina-silica carrier (63% Al_2O_3 /37% SiO_2); another good catalyst comprises 1% nickel and 8% molybdenum on an alumina-silica-boron phosphate carrier

containing 68% Al_2O_3 , 10% SiO_2 and 22% BPO_4 , the general preparation of which is described in U.S. Patent 2,938,001.

The present process may be further illustrated upon reference to the accompanying drawing which is a simplified flow diagram embodying the principal features of the invention insofar as they are capable of graphical representation. Heavy oil charge is introduced through line 1, mixed with hydrogen from line 19, and passed through combined feed preheater 2 wherein about 50-75% of the hydrocarbonaceous charge is vaporized. The heated mixed phase feed is passed via transfer line 3 and toroidal feed distributor 6 into the lower portion of vertical reactor 4 which contains a fluidized catalyst bed 5. Heated stripping and fluidizing hydrogen is fed to the bottom of reactor 4 from hydrogen preheater 17 through transfer line 18. The hydrogen is distributed through perforated plate 7 and flows upwardly around feed distributor 6 into catalyst bed 5 wherein the sorbed oil is hydrorefined and stripped from the catalyst particles. The upper portion of the reaction vessel comprises a particle separation zone 8 of enlarged cross-sectional area wherein the catalyst is disengaged from the mixed phase reactor effluent. A mixture of hydrogen, vaporized oil and entrained oil droplets is taken overhead through line 9, cooled in condenser 10 and passed to separator 11. Liquid product is withdrawn through line 13 and recycle hydrogen through line 12. Fresh outside hydrogen is added through line 14 and the total hydrogen is compressed by recycle gas compressor 15, thence discharged through line 16 to hydrogen preheater 17. A portion of the recycle hydrogen is taken off through line 19 and admixed with the heavy oil charge to suppress coking in heater 2. This proportion may range from 20% to 80% of the total recycle hydrogen flow. It is preferred, however, that a major proportion of the hydrogen be separately preheated in heater 17 and charged to the hydrorefining zone through line 18; in some cases, this stripping hydrogen may be heated to as much as 150° F. above the temperature of the combined feed in line 3, since it serves to raise the feed from preheat temperature to hydrorefining temperature which is best done in the simultaneous presence of hydrogen and catalyst to minimize thermal cracking. The stripping hydrogen is preferably heated to within the range of about 600-1000° F.

Various additions to and modifications of this flow scheme will be obvious to those skilled in the art. For example, a catalyst regenerator vessel may be connected with reactor 4 such that a dragstream of catalyst is continuously or intermittently regenerated by metal and coke removing techniques. The unit may be operated in conjunction with hydrogen production or purification facilities whereby a stream of hydrogen is continuously withdrawn from the recycle system to maintain hydrogen purity at a constant level, and make-up hydrogen may be added to line 1 instead of line 12. The hot overhead vapors in line 9 may be heat exchanged against heavy oil charge or recycle hydrogen prior to being cooled in condenser 10. A pipe grid may be substituted for perforated plate 7. Cyclone separators, electrical precipitators or other separation equipment may be used in lieu of, or in conjunction with, the enlarged area particle separation zone 8.

Representative charge stocks and processing conditions are set forth in the following examples. The charge stocks, temperatures, pressures, and flow rates there given are exemplary only and are not intended to limit the invention to any greater extent than as otherwise defined by the appended claims.

EXAMPLE I

A Wyoming sour crude oil is hydrorefined by the above-described continuous process in the presence of a pseudo-dry catalyst comprising 2% nickel and 16% molybdenum on a porous refractory support consisting of 68%

Al_2O_3 —10% SiO_2 —22% BPO_4 and having a particle size in the range of 10–150 microns. The Wyoming sour crude oil has a gravity of 22.5° API and contains 2.8% by weight of sulfur, 2700 p.p.m. of nitrogen, and 80 p.p.m. of vanadium and 20 p.p.m. of nickel as metallo-organic complexes; in addition, this sour crude comprises 8.3% by weight of pentane-insoluble asphaltenes. The crude oil is admixed with recycle hydrogen of 90% hydrogen purity in the ratio of 17,000 standard cubic feet per barrel of total oil charged, the mixture is preheated to 700° F. and charged to the hydrorefining zone. The weight ratio of total oil charged to catalyst contained in the hydrorefining zone per hour (WHSV) is 1.5. Stripping and fluidizing hydrogen is separately preheated to 850° F. and fed to the bottom of the hydrorefining zone in the ratio of 51,000 standard cubic feet per barrel. The fluid catalyst bed itself is maintained at a temperature of 800° F. under a total pressure of 2000 ps.i.g. Net hydrogen consumption is 1000 standard cubic feet per barrel. Liquid yield on a weight basis is 95%; the remaining 5% of the charge is converted to light gases as follows: 2% to C_1 – C_4 hydrocarbons, 1.9% to H_2S , 1.1% to H_2O . A comparison of the gravities and impurities levels of the total crude charge and liquid product is given in Table I.

Table I

	Total Crude Oil	Liquid Product
° API	22.5	31
Sulfur (Wt. percent)	2.8	0.9
Nitrogen	2700	1400
Vanadium	80	0.07
Nickel	20	0.03
C_6 -insolubles (Wt. percent)	8.3	0.03

EXAMPLE II

A topped Wyoming sour crude oil (90% of material boiling below 400° F. removed) is hydrorefined by the above-described continuous process in the presence of a pseudo-dry catalyst comprising 2% nickel and 16% molybdenum on a porous refractory support consisting of 63% alumina-37% silica and having a particle size in the range of 10–150 microns. The topped crude oil has a gravity of 19.5° API and contains 3% by weight of sulfur, 2850 p.p.m. of nitrogen, and 84 p.p.m. of vanadium and 21 p.p.m. of nickel as metallo-organic complexes; in addition, this topped crude comprises 8.5% by weight of pentane-insoluble asphaltenes. The topped crude oil is admixed with recycle hydrogen of 90% hydrogen purity in the ratio of 14,000 standard cubic feet per barrel of total oil charged, the mixture is preheated to 725° F. and charged to the hydrorefining zone. The weight hourly space velocity (WHSV) is 0.85. Stripping and fluidizing hydrogen is separately preheated to 820° F. and fed to the bottom of the hydrorefining zone in the ratio of 42,000 standard cubic feet per barrel. The fluid catalyst bed itself is maintained at a temperature of 775° F. under a total pressure of 2000 p.s.i.g. Net hydrogen consumption is 1070 standard cubic feet per barrel. Liquid yield on a weight basis is 95%; the remaining 5% of the charge is converted to light gases as follows: 2% to C_1 – C_4 hydrocarbons, 2% to H_2S and 1% to H_2O . A comparison of the gravities and impurities levels of the topped crude charge and liquid product is given in Table II:

Table II

	Topped Crude Charge	Liquid Product
° API	19.5	31
Sulfur (Wt. Percent)	3	1
Nitrogen	2850	1450
Vanadium	84	0.06
Nickel	21	0.03
C_6 -insolubles (Wt. Percent)	8.5	0.03

It will be observed from the data given in Examples I and II that vanadium removal exceeds 99.9%, nickel removal exceeds 99.8%, and conversion of pentane-insoluble asphaltenes is in excess of 99.6%. The 31° API product recovery is 95% by weight, which for a 22.5° API charge corresponds to a liquid volume yield of about 102%. Selective conversion of asphaltenes and metallo-organic complexes with minimum overall cracking is quite apparent in view of the high weight recovery and gravity reduction.

These beneficial results are obtained through the use of a pseudo-dry fluidized bed of absorptive catalyst particles obtained by partial feed vaporization, a high catalyst: feed ratio, and a high hydrogen:feed ratio. With respect to asphaltene conversion by autosolvent hydrorefining, the liquid phase converted asphaltenes sorbed in the catalyst particles act as an asphaltene solvent for incoming asphaltenes which upon conversion provide a continuous source of additional solvent.

I claim as my invention:

1. A process for hydrorefining a heavy hydrocarbon oil containing asphaltenes which comprises maintaining in a hydrorefining zone under hydrorefining conditions a pseudo-dry fluidized bed of absorptive hydrogenation catalyst particles, partially vaporizing said heavy oil by preheating it in the absence of catalyst to a temperature below that at which any substantial thermal cracking thereof can occur, introducing the partially vaporized oil into said hydrorefining zone and contacting it in the presence of hydrogen with said catalyst particles at asphaltene-hydrorefining conditions, sorbing unvaporized oil comprising hydrorefined asphaltenes into said catalyst particles to avoid any substantial accumulation of free liquid phase oil within the hydrorefining zone, flowing a hydrogen-containing gas upwardly through said hydrorefining zone and therewith stripping hydrorefined oil from the catalyst particles, withdrawing from said hydrorefining zone vaporous effluent and recovering therefrom a hydrorefining product of improved purity.
2. The process of claim 1 further characterized in that said heavy hydrocarbon oil is a crude oil.
3. The process of claim 1 further characterized in that said heavy hydrocarbon oil is a vacuum gas oil.
4. The process of claim 1 further characterized in that said heavy hydrocarbon oil is a heavy cycle oil.
5. The process of claim 1 further characterized in that said heavy oil is preheated in admixture with hydrogen.
6. The process of claim 1 further characterized in that said heavy oil is preheated to a temperature in the range of about 500–900° F.
7. The process of claim 1 further characterized in that said hydrorefining zone is maintained at a temperature in the range of about 650–950° F. and a pressure in excess of about 500 p.s.i.g.
8. The process of claim 1 further characterized in that a major proportion of said hydrogen-containing gas is preheated separately from the heavy oil charge to a temperature in the range of about 600–1000° F. prior to its introduction into said hydrorefining zone.
9. A process for hydrorefining a heavy hydrocarbon oil containing asphaltenes which comprises maintaining in a hydrorefining zone, at a temperature in the range of about 650–950° F. and a pressure in the range of about 500–5000 p.s.i.g., a pseudo-dry fluidized bed of absorptive hydrogenation catalyst particles; partially vaporizing said heavy oil by preheating it in the absence of catalyst to a temperature in the range of about 500–900° F. but below that temperature at which any substantial thermal cracking thereof can occur; charging the partially vaporized oil into said hydrorefining zone at a rate of about 0.25–20 pounds of total oil charged per pound of catalyst present in said zone per hour, and therein contacting said partially vaporized oil in the presence of hydrogen with said catalyst particles at asphaltene-hydrorefining

conditions; sorbing unvaporized oil comprising hydro-refined asphaltenes into said catalyst particles to avoid any substantial accumulation of free liquid phase oil within the hydrorefining zone; flowing a heated hydrogen-containing gas upwardly through said hydrorefining zone at a rate of about 5,000-300,000 standard cubic feet per barrel of oil charged and therewith stripping hydrorefined oil from the catalyst particles; and withdrawing from said hydrorefining zone vaporous effluent and recovering therefrom a hydrorefined product of improved purity.

10. A process for hydrorefining a heavy hydrocarbon oil containing asphaltenes which comprises the steps of:

- (1) partially vaporizing the oil by preheating it to a temperature below that at which any substantial thermal cracking thereof can occur;
- (2) maintaining in a hydrorefining zone under hydrorefining conditions a pseudo-dry fluidized bed of absorptive hydrogenation catalyst particles having sorbed therein a liquid-phase asphaltene solvent comprising hydrorefined asphaltenes;
- (3) introducing said partially vaporized oil into said hydrorefining zone and contacting it in the presence of hydrogen with said solvent-bearing catalyst particles at asphaltene-hydrorefining conditions;
- (4) sorbing unvaporized oil comprising hydrorefined

asphaltenes into said solvent-bearing catalyst particles whereby to avoid any substantial accumulation of free liquid phase oil within the hydrorefining zone, and dissolving in the particle-held solvent the asphaltenes contained in the sorbed oil;

- (5) converting said dissolved asphaltenes into additional asphaltene solvent;
- (6) flowing a hydrogen-containing gas upwardly through said hydrorefining zone and therewith stripping hydrorefined oil from the catalyst particles but leaving sorbed therein a portion of said asphaltene solvent;
- (7) contacting the resulting stripped solvent-bearing catalyst particles with additional incoming heavy oil; and
- (8) withdrawing from said hydrorefining zone vaporous effluent and recovering therefrom hydrorefined oil of reduced asphaltene content.
